UNITED STATES PATENT OFFICE.

LEANDER D. BERGER, OF PHILADELPHIA, PENNSYLVANIA.

DESIGN FOR A BUCKET-EAR.

SPECIFICATION forming part of **Design No. 21,567**, dated **May 24, 1892**.

Application filed April 8, 1892. Serial No. 428,391. Term of patent 14 years.

To all whom it may concern:

Be it known that I, LEANDER D. BERGER, a citizen of the United States, residing at Philadelphia, in the county of Philadelphia and State of Pennsylvania, have invented a certain new and useful Design for Bucket-Ears; and I do hereby declare the following to be a full, clear, and exact description of the invention, reference being had to the accompanying drawings, which form part of this specification.

My invention consists in the new and novel shape and surface configuration and ornamentation of a bucket-ear, all as hereinafter more specifically described and claimed.

My design relates both to the plate and the shank of the bucket-ear.

Referring to the accompanying drawings, in which Figure 1 is a front view, and Fig. 2 a side view, of a bucket-ear embodying my design, the upper edge of the plate A consists of two straight lines *b b*, which are continuations of the edge lines of the shank. The side

edges *c c* of the plate A are for the greater part of their length straight and are at right angles to the top lines of the plate. The bottom edges consist of two semicircular lines *d d*, which meet the rib C at the middle of the plate A. The plate A is perfectly plain except around the rivet-holes *a a*, where it is raised and formed in the shape of a star *c*. A flange or rib C extends from the eye *f* in the bail B to the point of juncture of the two bottom lines or edges *d d*, thus dividing the plate A into like sections.

Having thus described my invention, what I claim is—

The design for a bucket-ear, as shown and described.

In testimony that I claim the foregoing I have hereunto set my hand.

LEANDER D. BERGER.
